John H. Evans

Hedley Falla,
Fred Bergamini,
INVENTOR
BY *Victor J. Evans*

ATTORNEY.

UNITED STATES PATENT OFFICE

HEDLEY FALLA AND FRED BERGAMI, OF MILFORD, NEW HAMPSHIRE

CAN OPENER

Application filed March 25, 1927. Serial No. 178,341.

This invention relates to can openers and it is an improvement on the invention forming the subject matter of Patent No. 1,634,498, granted to the joint inventor Hedley Falla of the present invention.

The general object of the invention is to provide an improved can opener which includes means to prevent the knife of the opener from casually jumping out of a can during the operation of the opener and also to cause the knife of the opener to slide forward on its upstroke, with the result the present construction can be operated with extreme ease and will perform its functions in an efficient and expeditious manner with very little effort on the part of the operator.

This invention also consists in certain other features of construction and in the combination and arrangement of the several parts, to be hereinafter fully described, illustrated in the accompanying drawings and specifically pointed out in the appended claim.

In describing our invention in detail, reference will be had to the accompanying drawings wherein like characters denote like or corresponding parts throughout the several views, and in which:

Figure 1 is a perspective view of one form of the present invention.

Figure 2 is a view of the construction as shown in Figure 1 with the blade in a downwardly applied position in a can.

Figure 3 is a similar view of the opener as shown in Figure 2 with the blade in an upwardly applied position.

Figure 4 is a perspective view of the knife blade and shank therefor.

Figure 5 is a sectional view taken on line 5-5 of Figure 4.

Referring to the drawings in detail and particularly to Figures 1 to 5 inclusive, the reference numeral 1 indicates the blade of the can opener as shown in these figures and which is formed with a body 2 and said body is curved intermediate its ends in a manner to dispose the ends substantially at right angles with respect to each other as best shown in Figure 4 of the drawings.

A shank 3 is formed with the body 2 and

is adapted to receive a handle 4 of the usual construction.

Pivottally secured to the body 2 adjacent its juncture with the blade 1 is a yoke 5 of substantially U-shape configuration and includes an arm 6 disposed upon the inner side of the blade while the arm 7 thereof is bent rearwardly upon itself as at 8 and is fixed in said position through the instrumentality of the pivot pin 9 which secures the yoke to the blade as above set forth. Formed integral with and depending from the curved portion 10 is a guide member 11 which co-operates with a reduced portion formed with and depending from a guide member 11', and these guides are adapted to contact with the outer surface of the wall of a can which is indicated by the letter A in Figures 2 and 3.

It will be noted that the construction thus far described is substantially the same as the prior invention above identified, with the exception that the body portion 2 presents an improvement as well as the curved portion 10 of the arm 7. The blade 1 is beveled in the usual manner to provide a cutting edge, and it will be noted that the cutting edge adjacent its outer end is provided with a notch 12, but said cutting edge terminates in a point 13 as clearly shown in the drawing. The blade is further formed with a recess 14 disposed adjacent its juncture with the body portion 2, and the purpose of this recess 14 which as shown is concaved in configuration, is to provide for easy forward sliding of the blade on its upstroke as suggested in Figure 2 of the drawing while the notch 12 in the cutting edge of the blade is to prevent the latter from jumping out of the can on its upstroke as clearly shown in Figure 3 of the drawing, as it will be noted that this notched end will engage the uncut portion of the metal for the purpose set forth.

From the above description and disclosure of the drawings, it will be obvious that the improved can opener includes many advantageous features and by curving the body 2, the same will cooperate with the recess 14 to allow the knife to be easily slid forward on

its upstroke as it will be obvious that the recess will reduce the thickness of the blade and thereby the edges of the cut made by the blade will offer minimum resistance if any at the reduced portion.

5 It is thought from the foregoing description that the advantages and novel features of our invention will be readily apparent.

We desire it to be understood that we may
10 make changes in the construction and in the combination and arrangement of the several parts, provided that such changes fall within the scope of the appended claim.

What we claim is:

15 A can opener of the character described comprising a blade, a curved body for said blade, guide means for said blade and including a substantially U-shaped yoke having one arm bent rearwardly upon itself, a
20 projection included in said guide means for engaging the outer wall of a can and being formed with and depending from the rearwardly bent portion, means for pivotally securing said curved body to said guide
25 means and passing through the rearwardly bent portion, a guide member formed with the other arm of the U-shaped yoke, a reduced portion depending from the guide member and being aligned with the projection for cooperation therewith, said blade
30 being recessed adjacent its juncture with its body, said blade including a cutting edge and said edge being notched at its outer end.

35 In testimony whereof we affix our signatures.

HEDLEY FALLA.
FRED BERGAMI.
